UNITED STATES PATENT OFFICE.

HARRIET WEBSTER FOWLER, OF NEW YORK, N. Y., ASSIGNOR TO CHENEY BROTHERS, OF SOUTH MANCHESTER, CONNECTICUT, A CORPORATION OF CONNECTICUT.

DESIGN FOR A TEXTILE FABRIC.

No. 38,123.

Specification for Design.

Patented July 3, 1906.

Application filed May 25, 1906. Serial No. 318,786. Term of patent 3½ years.

To all whom it may concern:

Be it known that I, HARRIET WEBSTER FOWLER, a citizen of the United States, residing in the borough of Brooklyn, city of New York, in the county of Kings and State of New York, have invented a new, original, and ornamental Design for Textile Fabrics, of which the following is a specification, reference being had to the accompanying drawing, forming a part thereof.

The figure is a plan view of the fabric, showing my new design.

I claim—

The ornamental design for a textile fabric, as shown.

HARRIET WEBSTER FOWLER.
